(57) **CLAIM**

The ornamental design for a cover for terminated cables, as shown and described.

DESCRIPTION

FIG. 1 is a perspective view of a cover for terminated cables illustrating the new design;

FIG. 2 is a front side view thereof;

FIG. 3 is a right side view thereof;

FIG. 4 is a top side view thereof; and,

FIG. 5 is a bottom side view thereof.

In FIGS. 1-5, the broken lines illustrating an end portion of a terminated cable, an attachment segment, and a rolling feature are for illustrative purposes only and form no part of the claimed design.
